[57] CLAIM

The ornamental design for a tire tread, as shown and
described.

DESCRIPTION

FIG. 1 is a perspective view of a tire tread showing my new
design, it being understood that the tread pattern repeats
uniformly throughout the outer surface and shoulder cir-
cumference the tire tread, the opposite side perspective view
being identical thereto; and,

FIG. 2 is a enlarged fragmentary front elevation view of the
tire tread thereof.

The broken line disclosure of the tire sidewall and inner bead
is for illustrative purposes only and forms no part of the
claimed design.
